UNITED STATES PATENT OFFICE.

ISRAEL REID, OF WASHINGTON, DISTRICT OF COLUMBIA.

REMOVABLE BUTTON.

1,146,652.

Specification of Letters Patent.

Patented July 13, 1915.

Application filed March 3, 1915. Serial No. 11,796.

To all whom it may concern:

Be it known that I, ISRAEL REID, a subject of the King of England, residing at Washington, in the District of Columbia, 5 have invented a new and useful Removable Button, of which the following is a specification.

The device forming the subject matter of this application is a button adapted to be assembled with one flap of a garment and constructed to coöperate with a button hole in the other flap of the garment.

The invention aims to provide novel means whereby the head portion of the button may be rapidly and securely but detachably assembled with one flap of the garment.

Another object of the invention is to provide a button of the type described having 20 an element of novel form adapted to be received within the button hole of one flap of the garment.

Another object of the invention is to provide a novel means whereby the bail-shaped 25 retaining member may be held parallel to the head of the button and parallel to the flaps of the garment.

A further object of the invention is to provide in a button of the type described, a 30 pair of plates of novel form, the plates being interchangeable, the plates coacting to form a means for engaging one flap of the garment, one plate being capable of being received in the button hole of the other flap 35 of the garment.

It is within the scope of the disclosure to improve generally and to enhance the utility of devices of that type to which the present invention appertains.

With the above and other objects in view 40 which will appear as the description proceeds, the invention resides in the combination and arrangement of parts and in the details of construction hereinafter described 45 and claimed, it being understood that changes in the precise embodiment of the invention herein disclosed can be made within the scope of what is claimed, without departing from the spirit of the invention.

50 In the accompanying drawing: Figure 1 shows the invention in front elevation assembled with a portion of a garment; Fig. 2 shows the invention in rear elevation, assembled with a portion of a garment, parts 55 of the button being sectioned and broken away; Fig. 3 is a section on the line 3—3 of

Fig. 1; Fig. 4 is a section on the line 4—4 of Fig. 1; Fig. 5 is a perspective showing one of the plates which are carried by the studs of the button; Fig. 6 is a perspective 60 view showing the head of the button and the studs thereon; Fig. 7 is a perspective view delineating the retaining member.

The button herein disclosed may be fashioned from any desired material, and comprises a head 1 of any desired outline and contour. Projecting rearwardly or inwardly from the head 1 and ordinarily formed integrally therewith are spaced 65 studs 2 preferably circular in cross section. 70 Near to their free ends, the studs are equipped with transverse openings 3.

The invention comprises an inner plate 4 provided with spaced openings 5 adapted to receive the studs 2 on the head 1. The invention further includes an outer plate 6 having openings 7 through which the studs 2 pass. The plates 4 and 6 preferably are duplicates of each other, and each plate in plan approximates roughly the cross section 80 of a double-convex lens.

The invention comprises a retaining member in the form of a resilient bail 8 bent upon itself to form laterally extended arms 9 terminated in free fingers 10. Intermediate 85 their ends, the arms 9 are contracted as shown at 11, thereby to form at the bent end of each arm, a resilient enlargement 16. The arms 9 of the bail 8 are detachably and pivotally mounted in the openings 3 of the 90 studs 2.

The numeral 12 denotes one flap of a coat or other garment, which element may be described as a button carrying strip. The other flap 14 of the garment may be described 95 as a button engaging strip, and is provided with a button hole 15.

In practical operation, the inner plate 4 is slipped over the studs 2 and brought into abutment with the under or inner face of 100 the head 1. The studs 2 then are inserted through suitable openings 17 in the strip 12, the outer plate 6 is mounted on the studs 2, and the bail-shaped retaining member 8 is first contracted and then permitted to expand, its arms 9 entering the openings 3 in 105 the studs 2 and serving to hold the button assembled with the strip 12.

The button hole 15 in the strip 14 is passed over the head 1 of the button and surrounds 110 the inner plate 4 closely. Especial attention is directed at this point to the fact that the

plate 4 is so shaped as to conform to the outline of the button hole 15. The plate 4, further, serves to space the inner or under face of the head 1 apart from the button carrying strip 12, so that the button hole 15 in the strip 14 may be engaged readily about the plate 4 and beneath the head 1. The plates 4 and 6, it is to be noted, serve to clamp between them the button carrying strip 12. Owing to the fact that the plate 4 is removable, the same may be dispensed with if desired. Since the plates 4 and 6 are exactly alike, the plates are interchangeable and but one form of plate is used, the 15 cost of the device being decreased accordingly.

After the parts have been assembled as above described, the resilient bail 8 is turned over sidewise, so that it lies approximately 20 parallel to the head 1 and parallel to the strip 12 of material, the object in thus disposing the retaining member in an out-of-the-way position being entirely obvious. It is essential and important that the bail-shaped retaining member 8 remain in the 25 position shown in Figs. 3, 4 and 2, that is, parallel to the strip 12. Attention, therefore, is directed to the construction of the arms 9, whereby this result is brought about. 30 When the arms 9 are inserted into the openings 3 of the studs 2, the resilient enlargements 16 in the ends of the arms 9 rest yielding against the walls of the openings 3. Further, since the arms are contracted, as 35 shown at 11, the free ends of the arms also bear against the walls of the openings 3. Thus, each arm 9 is given a double grip upon the walls of the openings 3 and a movement of the bail-shaped retaining member 8 out 40 of the positions shown in Figs. 3, 4 and 2 is not likely to occur.

Having thus described the invention, what is claimed is:—

1. A button comprising a head and spaced 45 studs assembled with the head, the studs having openings; and a resilient, bail-shaped retaining member embodying lateral arms detachably engaged in the openings.

2. A button embodying a head and spaced

studs assembled with the head, the studs 50 having openings; a resilient, bail-shaped retaining member embodying lateral arms engaged in the openings; and a plate having openings receiving the studs, the plate being located between the head and the arms of 55 the retaining member.

3. A button comprising a head and spaced 60 studs assembled with the head, the studs having openings; and a resilient, bail-shaped retaining member including arms detachably engaged in the openings and pivotally mounted therein to permit the retaining member to lie parallel to the head, one of the arms being U-shaped and being contracted to form a resilient enlargement and 65 a free finger which engage one stud at spaced points in the opening therein, thereby to form a double grip effective to hold the retaining member parallel to the head.

4. A button comprising a head and spaced 70 studs assembled with the head, the studs having openings; and a resilient, bail-shaped retaining member including lateral arms detachably engaged in the openings, and pivotally mounted therein to permit the retaining 75 member to lie parallel to the head, one of the arms being U-shaped and being resiliently expandible in the opening of one stud, thereby to hold the retaining member in parallel relation to the head.

5. A button comprising a head and a stud 80 projecting from the head; a pair of plates through which the stud passes; and stud carried locking means coöperating with one plate; the plates being of like construction, 85 to provide an interchangeable mounting thereof upon the studs, the plates coöperating to form a material engaging means, and one plate being located adjacent the head and constituting a button hole entering element.

In testimony that I claim the foregoing as my own, I have hereto affixed my signature in the presence of two witnesses.

ISRAEL REID.
